INVENTOR,

Sidney W. Bollinger,
by Wm. L. Pierce,
his Attorney.

UNITED STATES PATENT OFFICE.

SIDNEY W. BOLLINGER, OF PITTSBURG, PENNSYLVANIA.

CAR-HAUL.

SPECIFICATION forming part of Letters Patent No. 707,200, dated August 19, 1902.

Application filed September 20, 1901. Serial No. 75,917. (No model.)

To all whom it may concern:

Be it known that I, SIDNEY W. BOLLINGER, a citizen of the United States, residing at Pittsburgh, in the county of Allegheny and State of Pennsylvania, have invented or discovered new and useful Improvements in Car-Hauls, of which the following is a specification.

In the accompanying drawings, which make part of this specification, Figure I is a side elevation of the down-haul chain, showing the supporting-plate and guide in section. Fig. II is a detail perspective of links and hooks. Fig. III is a cross-section on line III III of Fig. I, showing a hook raised and its bottom in contact with the supporting-plate. Fig. IV is a cross-section on line IV IV of Fig. I, showing a hook lowered and its lower end between the guides.

The object of my invention, generally stated, is to provide means for the automatic handling of mine-cars on the down-haul chain of a car-haul.

In the general arrangement of the down-haul chain the gravity portion of said chain is shown in the drawings as on an incline; but it is not necessary to so arrange that portion of the chain, as a horizontal position will answer the same purpose when check-brakes of any of the well-known patterns are provided to check the cars at that point.

I have provided simple and efficient means for pushing cars forward from the gravity-section of the chain to the downgrade and also for controlling cars while on the downgrade.

In the accompanying drawings, 1 represents an endless chain. 2 is an idler-wheel, and 3 are sprocket-wheels located at each end of the loop. Only one is shown in the drawings.

The chain 1 consists of links arranged in pairs and at suitable points, having pivoted hooks 4 and 5, arranged so as to engage the car 6 in opposite directions.

Hook 4 is pivotally connected to the links 7 and 8 and is provided with an overbalanced end 8.

Hook 5 is pivotally secured to links 11 by means of pin 12.

13 is a slot in the forward end of hook 5. Pin 14, secured to the link 11, passes through slot 13 and acts as a stop in the swinging movement of said hook. Preferably these

hooks are located between the links. They could, however, be located at either side of the links without departing from my invention.

55

15 represents a support for chain 1.

16 is a slot formed between the downwardly-extending flanges of support 15.

17 is a channel-shaped guide for the chain 1 on the downgrade portion of the chain. 60

In the operation of my invention a car after being unloaded and returned in the usual manner over the customary cross-over switch and extension-track runs by gravity down and over sprocket-wheel 3 and along the rails (not shown) at each side of chain 1. The inclination of the track at position 9 causes the car to slow down and stop. As the car 6 is moving forward over the chain 1 to its stopping position bar 10, which is secured to the car, 70 will knock down and pass over hook 4, after which the hook immediately assumes its proper position.

In the chain's forward travel the hook 4 engages the bar 10 of car 6 and moves the car 75 forward and over the idler-wheel 2. Hook 5 after passing over sprocket-wheel 3 drops to its lowest position, which permits the bar 10 to pass over. The lower portion of the hook enters the slot 16 and travels along said slot 80 until idler-wheel 2 is reached, when it raises up out of the slot and assumes its highest position, remaining up and next enters the channel 17. The bottom of the channel holds the hook up in position to engage bar 10. After 85 hook 4 has pushed car 6 over the idler-wheel 2 the car pitches forward slightly and the bar 10 comes into contact with hook 5, holding the car in check and traveling down the grade at whatever speed the chain travels. 90

Having described my invention, I claim—

1. In a car-haul, a chain, hooks pivotally secured thereto and arranged so that alternate hooks engage a stop on a car in opposite directions.

2. In a car-haul, a chain-support, a slot in said support, a chain, a hook pivotally secured to said chain and a second chain-support, said chain-supports and said slot providing means for lowering and raising the end 100 of said hook.

3. In a car-haul chain, a hook pivotally se-

cured at one end to the link of said chain, a slot in said hook and a pin through said slot and secured to said link.

4. In a car-haul, a car having a stop, a chain, 5 a hook pivotally secured thereto and means for raising the hook independent of the chain so as to engage the stop on said car.

Signed at Pittsburg this 18th day of September, 1901.

SIDNEY W. BOLLINGER.
